AIR PREHEATER FOR FURNACES AND
THE LIKE

Marek Steuerman, London, England

Application January 8, 1944, Serial No. 517,601
In Great Britain March 26, 1942

4 Claims. (Cl. 110—175)

1

This invention concerns air preheaters for furnaces and the like of the kind adapted to be mounted on the inside of the fire door or in any other suitable convenient position for the purpose of preheating air passing into the furnace above the fire grate with the object of obtaining improved combustion of the fuel on such grate, such preheaters each comprising a hollow body adapted to be heated by the fire in the furnace and constricted so that air, or some air, on its 10 way into the furnace may pass through the preheater and be preheated prior to entering the fire space.

An object of this invention is to provide an improved form of air preheater, and according to the invention there is provided an air preheater of the kind referred to for furnaces and the like, wherein within the hollow body, and behind the front wall (i. e., the wall presented to the fire) thereof, is arranged a flap or partition dividing the hollow body into two compartments, such flap or partition being movable towards and away from the said front wall to control the flow of air through the space between the front wall of the hollow body and the such flap or partition, and wherein means are also provided for adjusting the position of such flap or partition preferably from the exterior of the hollow body.

More particularly the invention is concerned with air preheaters of the kind referred to and in which baffle means are provided within the hollow body to ensure that the air to be preheated will take a tortuous path through the hollow body. Therefore, according to a further feature of the invention baffle means are arranged between the said movable flap or partition and the said front wall of the hollow body to define one or more tortuous paths to which the air passing through the space between the front wall of the hollow body and the movable flap or partition must pass. Preferably the said baffle means are constituted by co-operating interleaved baffles carried respectively upon one surface of the said movable flap or partition and on the opposite inside surface of the said front wall of the hollow body.

Preferably, but not necessarily, the arrangement of the said baffle means is such that the air to be preheated passes tortuously backwards and forwards in the hollow body (i. e. transversely of the said movable flap or partition and the front wall of the hollow body), the air preferably entering the tortuous path provided by the baffle means at or near the lower part of the hollow body, gradually rising to, and leaving the tor-

2

tuous path at or near the upper part of the hollow body. After leaving this tortuous path the air may be discharged directly into the furnace through one or more openings in the front wall and/or top and/or ends of the hollow body or in any other suitable way, or a supplementary or superheating chamber may be provided at the upper portion of the preheater, which chamber may project forwardly beyond the front face of the front wall of the hollow body, and which may have a rectilinear, curved, or otherwise suitably shaped front wall in which is or are arranged one or more discharge apertures.

The arrangement is preferably such that air is admitted into the space between the movable flap or partition and the front wall of the hollow body through a gap between these two parts, the closing or opening of the said gap and the extent to which it is opened being obtained and 15 regulated by adjusting the movable flap or partition with respect to the front wall of the hollow body. Preferably said gap is provided at the lower part of the hollow body and is constituted on the one hand by a longitudinal seat formed 20 upon the inside of the front wall of the hollow body, and on the other hand by the front surface of the adjustable flap or partition which is adapted, in the closed position of the flap or partition, to seat upon the said seat, thus closing 25 the gap entirely. Assuming the preheater to be set with its rear wall vertical, the said longitudinal seat, which is preferably horizontal, is conveniently disposed at a short distance from the bottom of the hollow body and at a location intermediate 30 the front wall and the back of the hollow body, and the said movable flap or partition preferably extends from end to end of the hollow body and from the top thereof to a position somewhat below the said seat so that the movable flap or 35 partition, with the said seat, separates the said two compartments of the hollow body from one another, a slot-like portion being left, however, adjacent the bottom of the hollow body so as to serve as an air inlet for the entry of air into 40 the hollow body and to the said regulatable gap between the movable flap or partition and the said seat on the front wall. Alternatively, the said adjustable flap or partition may extend to the bottom of the hollow body and be provided 45 with a hole or holes for the passage of air therethrough at positions below the seat of the front wall.

Preferably the front wall of the hollow body is formed internally with a series of side by side 50 parallel but somewhat spaced channels arranged

one above the other and extending longitudinally of the hollow body, and between these channels are arranged the hereinbefore mentioned baffles which extend parallel to the channels and backwardly from the said front wall. Similarly the front side of the said movable flap or partition is correspondingly formed, but the channels and baffles of this flap or partition are offset with respect to those of the front wall, so that the baffles of the flap or partition project more or less centrally into the channels of the front wall, and vice versa.

The front surface of the front wall may be ridged or corrugated to increase its area and so to increase the heat exchange surface thereof. Conveniently this front surface of the front wall of the hollow body is corrugated or ridged longitudinally, the crests of the corrugations following in shape, and coinciding in position with, the bottoms of the channels in the rear side of the front wall, which bottoms are preferably of semi-cylindrical form (i. e., semi-circular in cross-section). Thus the front surface of the front wall of the hollow body will appear to be made up of a series of parallel side by side superposed strips or bars, the front surface of each of which is of part cylindrical form. The channels and baffles of the said flap or partition may be shaped and arranged similarly to those of the front wall of the hollow body and the baffles of both the latter and the said flap or partition may taper towards their free longitudinal edges.

A back plate may be provided to close the rear of the hollow body, or instead of using a back plate the furnace door may be relied upon to effect the closing of the rear of the hollow body. If, however, a back plate is used, then it is provided with one or more air inlet openings. Such inlet opening or openings may be at any suitable position and of any convenient shape and size, but preferably a single opening is provided at the lower part of the back plate, this opening being of elongated slot-like form extending almost from end to end of the plate and having its upper edge coinciding with the lower edge of the said movable flap or partition.

Preferably the front wall of the hollow body is backwardly and downwardly inclined with respect to the plane passing through the rear edges of the walls of the preheater, so that, regarding the preheater in end elevation, it appears to decrease in depth (from front to back) in a direction from the top towards the bottom, i. e. it is of wedge shape in end elevation.

Preferably the said movable flap or partition is pivotally mounted at its upper end in the hollow body, and screw and nut means are preferably provided on or near its lower end for adjusting the flap or partition, the screw part of the adjusting means being extended so as to project rearwardly of the preheater and being adapted to pass through the furnace door and to be provided with a handle or knob at its outer end so that the required adjustments may be made from the exterior of the furnace.

In order that the invention may be thoroughly understood and readily be carried into practice, drawings are appended hereto in which:

Figure 1 is a front elevation of one form of preheater constructed according to this invention;

Figure 2 is an end elevation of the same;

Figure 3 is a section on line 3—3, Figure 1;

Figure 4 is a back elevation of the preheater shown in Figures 1 to 5 partly broken away in

successive sections to expose otherwise hidden parts of the interior construction of the preheater;

Figure 5 is a section on line 5—5, Figure 4; and

Figure 6 is a perspective view of the flap or partition in the interior of the preheater.

The air preheater illustrated in the drawings is intended to be attached to the inside of a furnace door. The preheater comprises a hollow body 1 of rectangular form as seen from the rear. From back to front it is relatively shallow as compared with its length and breadth and its front wall 2 inclines backwardly and downwardly slightly so that it is rather nearer the rear of the hollow body at the bottom thereof than it is at the top.

At its upper end the front wall 2 is externally and internally extended forwardly at 3 so as to provide a longitudinal forwardly extending chamber 4. The front wall 5 of this chamber is rectilinear and parallel to the back edge of the top wall 6 of the hollow body, but the said front wall could be curved, e. g., convex, or inclined forwardly from its ends towards its centre if desired. The wall 5 is provided with a row of air discharge openings 7 which are conveniently circular in cross-section and of frusto conical form, the narrower ends of the holes being their forward ends. The axes of the holes may be horizontal or somewhat downwardly inclined and they may or may not be parallel as seen in plan; for example, the axes of the holes as seen in plan may splay outwards somewhat in the manner of the thumb and fingers of an extended hand, or they may converge towards one another in a forward direction. Except for the discharge holes above mentioned the front of the hollow body is entirely closed.

The bottom wall 8 of the hollow body is of a sinuous or ogee form in cross-section, so that inside the hollow body the bottom is on two levels, that is to say, the bottom consists of two longitudinal horizontal steps, a lower rear step 9 and a higher forward step 10 separated by a substantially vertical longitudinal part or "riser" 11. The rear edge of the said forward step is provided with a backwardly directed ridge or flange 12 which extends from end to end of the hollow body and overhangs the more or less vertical part or "riser" 11. This backwardly directed ridge or flange 12 constitutes a seat upon which is adapted to sit, in certain circumstances, the lower part of a hinged flap or partition 13 subsequently to be more fully described.

Between the part of the bottom wall 8 of the hollow body and the bottom wall 14 (which wall also serves as a baffle) of the said chamber 4, and within the hollow body, are arranged a plurality of longitudinal parallel preferably equally spaced baffles 15 which are formed in one with the inside surface of the front wall 2 of the hollow body and extend from end to end of the latter, parallel to the bottom 8 of the hollow body and backwardly from the said front wall 2 so as to have their rear edges substantially flush with the rear edge of the said longitudinal seat 10. This rear seat edge, and the rear edges of all the above-mentioned baffles, are spaced some distance from the plane containing the rear edges of the top and bottom walls 6 and 8 and the side walls 16 and 17 of the hollow body, and since the baffles 15 are preferably all of the same width from back to front as one another, and as the front wall 2 of the hollow body inclines

downwardly towards the back of the hollow body, the rear edges of the baffles are consequently spaced progressively further away from the said plane containing the rear edges of the top and bottom and side walls of the hollow body, starting from the bottom baffle and travelling towards the upper baffle.

The inside surface 18 of the front wall 2 of the hollow body is, between each pair of baffles 15 and between the step 10 and the next baffle 10 and between the top baffle 15 and the lower wall 14 of the said chamber 4, is shaped to substantially semi-cylindrical concave form as seen from the back, and the outer front surface of the front wall 2 is correspondingly shaped so that the front wall of the hollow body has a plurality of longitudinal parallel convex ribs 19 projecting therefrom, the longitudinal grooves or depressions 20 between which ribs correspond in position with the baffles within the hollow body. Additional 15 ribs, fins, corrugations or projections may be provided on the hollow body if desired further to increase the area of the heat exchange surfaces.

The front wall 2 also has a flattened portion 39 on which may be carried the maker's name or 25 other data.

The hinged flap or partition 13 above referred to is disposed within the hollow body 1, and comprises a rectangular plate which is of a length substantially equal to the distance between the inside surfaces of the two end walls 16 and 17 of the hollow body, but which plate is of a depth from top to bottom somewhat less than the depth of the hollow body from top to bottom at the rear thereof.

Adjacent its upper edge, the said plate is provided with a rib 21 carrying a trunnion 22 at each end (Figure 5) and each of these trunnions seats in a bearing 23 (Figure 4) provided at the adjacent end wall of the hollow body, and the trunnion is rotatably secured in that position by a cover piece 24 recessed into the back edge of the end wall of the hollow body and secured in position by one of the screws used to secure the back cover plate 25 (subsequently to be described) in position. When hinged in the hollow body 1 the upper edge of rib 21 of the flap or partition 13 lies adjacent the inside surface of the top wall 6 of the hollow body.

On its inner side the flap 13 is provided (see Figure 6 in particular) with a plurality of equally spaced parallel longitudinal baffles 26 which are preferably cast integrally with the plate, the plate, in cross-section, being of semi-cylindrical form between each pair of baffles as shown at 27. The baffles 26 on the flap 13 are similar to the baffles 15 on the inside of the front wall 2 of the hollow body 1, but when the hinged plate is in position in the hollow body, the baffles 26 of the flap are offset with respect to the baffles 15 on the hollow body so that the latter baffles project into the spaces between the baffles on the flap. However, the baffles on the movable flap and those on the front wall of the hollow body are preferably of such dimensions that the baffles on the one part never touch the bottoms of the grooves between the baffles of the other part.

The flap 13 projects downwardly below the lowermost baffle 26 on the plate so as to provide a longitudinally extending dependent flange 28 which is adapted, in the closed position of the flap, to seat upon the hereinbefore mentioned seat 12, provided on the hollow body, so as to prevent the ingress of air to the space 29 between the inner surface of the front wall 2 of the hollow body

and the front surface of the hinged flap. Thus the cooperating parts 12 and 23 act as a form of valve.

On the back of the hollow body is secured, by screws, the metal back cover plate 25 which is formed of metal and which has a portion of elongated rectangular form cut out of its lower edge to form an air inlet opening 30 opposite the space between the bottom edge of the said hinged flap 13 and the lower and rearmost step-like part 9 of the bottom 8 of the hollow body.

For the purpose of adjusting the hinged flap 13 towards and away from the front wall 2 of the hollow body, a screwed stem 31 is provided which is mounted for rotatory, but non-axial, movement in a sleeve 32 screwed into the back plate 25 at the lower part of, and perpendicularly to, the latter. The said sleeve is adapted to pass through the furnace door, and the sleeve and screwed stem are of such a length as to be capable of projecting beyond the outer side of the furnace door whilst the stem 31 also extends into the hollow body 1 and into the said hinged flap 13. The outer end of the screwed stem 31 is provided with a knob 33 for rotating it, and at its inner end 34 the stem is screwed into a nut 35 which is housed in a non-rotatable manner in a recess 36 provided at the lower central part of the hinged flap 13 and closed by a plate 37.

Preferably the top, bottom and side or end walls of the preheater slope inwardly towards the front wall thereof.

In use the preheater is fixed, for example by studs 38 within the furnace, for example flat against the inside surface of the furnace door to the outside thereof so that the knob 33 can be manipulated from the outside of the furnace. The gap 30 at the lower part of the preheater is registered with a corresponding gap or with one or more air inlet holes provided in the furnace door.

The front wall 2 of the preheater is therefore presented in a somewhat oblique position to the fire within the furnace and in operation air enters through the gap 30 and rises within the preheater between the part 28 of the flap or partition 13 and the seat 12 and then passes in a tortuous backward and forward manner up through the preheater into the forwardly projecting chamber 4 and eventually out of the discharge holes 7 in the upper forwardly projecting portion or bulge 5 of the preheater, the air so leaving the preheater being directed towards the fire.

If the discharge holes 7 are arranged with their axes downwardly inclined then the streams of air issuing from these holes will be biased in a downward direction. The flow of air through the preheater is regulated by adjusting the flap or partition 13 to and away from the front wall 2 of the preheater by means of the adjusting screw 31 and the associated parts, this screw being operated by the knob 33 from the exterior of the furnace. If desired, the intake of air can be entirely shut off by adjusting the flap or partition 13 so that the part 28 thereof bears against the seat 12.

I claim:

1. An air preheater for furnaces and the like comprising a hollow body, its top wall being substantially imperforate, its rear wall being provided adjacent its bottom edge with air inflow means, the rear wall being otherwise substantially imperforate, the front wall of said hollow body being provided with air outflow means adjacent

its upper edge, the front wall being otherwise substantially imperforate, the inner face of the front wall being provided with baffle-like formations extending generally in like directions and transversely to the direction from said air inflow means to said air outflow means; a plate disposed within said hollow body intermediate the inner face of said rear wall and said baffle-like formations of said front wall, said inwardly disposed plate having baffle-like formations facing said baffle-like formations of said front wall and generally in like directions and extending transversely to the direction from said air inflow means to said air outflow means, the free edges of said baffle-like formations of said inwardly disposed plate being disposed alternately with respect to the free edges of said baffle-like formations of said front wall; means for pivotally mounting said inwardly disposed plate at its upper portion; and means extending through said rear wall for adjusting the pivotal position of said inwardly disposed plate.

2. An air preheater pursuant to claim 1 in which said baffle-like formations at the inner face of the front wall and said baffle-like formations of said inwardly disposed plate extend mutually in parallel directions.

3. An air preheater pursuant to claim 1 in which said baffle-like formations at the inner

face of the front wall and said baffle-like formations of said inwardly disposed plate extend mutually in parallel directions and substantially at right angles to the direction from said air inflow means to said air outflow means.

4. An air preheater for a furnace or the like, comprising a hollow box-like body, such body including a rear wall provided with air inlet means at its lower part and including a front wall having air discharge means at its upper part, a flap mounted within said body between said front and rear walls and pivotable about its upper end, means operable from the exterior of said rear wall for moving the lower end of said flap towards or away from said front wall, a shoulder on said front wall co-operating with the lower end of said flap to form a variable air inlet to the space between the flap and the front wall, a plurality of baffles on said front wall projecting into said space between the flap and front wall, the parts of the rear face of said front wall between said baffles being of semi-cylindrical form, a plurality of baffles on said flap, such baffles extending towards said front wall and being offset relatively to the baffles on said front wall, and the parts of the front face of said flap between the baffles thereon being of semi-cylindrical form.

MAREK STEUERMAN.
